UNITED STATES PATENT OFFICE.

CHARLES M. BULLER, OF MILWAUKEE, WISCONSIN, ASSIGNOR TO L. J. MUELLER
FURNACE COMPANY, OF MILWAUKEE, WISCONSIN, A CORPORATION OF WIS-
CONSIN.

PIPELESS FURNACE.

Application filed June 23, 1919. Serial No. 305,982.

To all whom it may concern:

Be it known that I, CHARLES M. BULLER, a citizen of the United States, and resident of Milwaukee, in the county of Milwaukee 5 and State of Wisconsin, have invented new and useful Improvements in Pipeless Furnaces, of which the following is a description, reference being had to the accompanying drawings, which are a part of this specification.

The present invention relates to certain new and useful improvements in furnaces of the hot air conductor type, in which cold air and hot air ducts have co-incident terminals 15 above the heater.

An object of the present invention is to provide a novel form of passageway leading from the heating chamber to the hot air passageway which is formed of two complementary members each struck from a plain sheet 20 of metal and then crimped or ribbed to provide upwardly and inwardly inclined reinforced walls.

Another object is to provide a furnace in 25 which the heater is surrounded by two chambers inter-communicable at the base, the outer one providing a cold air chamber and the second inner one providing a hot air chamber, both of the chambers having the 30 casings defining the same opened at a portion of their walls to provide a passageway for the heater doors, and means carried by the inner casing at its ends adjacent the opening therein for resilient engagement 35 with the outer casing adjacent its ends defining the opening therein whereby said cold air chamber and hot air chamber will be non-communicable.

A further object of the present invention 40 is to provide a furnace having a heater, an outer casing, and a drum within the casing and surrounding the heater and means for vertically adjustably supporting said drum within the heater whereby the same may be 45 readily adapted for use with heaters of various heights and sizes.

A still further object of the present invention is to provide a furnace of the type described in which the parts are readily inter-changeable with furnaces of the same 50 type of various sizes, and which will be simple of construction and extremely inexpensive to produce.

With the above and other objects in view 55 which will appear as the description pro-

ceeds, my invention resides in the novel construction, combination and arrangement of parts substantially as hereinafter described and more particularly defined by the appended claims, it being understood that such changes in the precise embodiment of the hereindisclosed invention may be made as come within the scope of the claims.

In the accompanying drawings, I have illustrated one complete example of the physical embodiment of my invention constructed according to the best mode I have so far devised for the practical application of the principles thereof, and in which:

Fig. 1 is a sectional view of a complete furnace embodying my various features, said view having parts broken away and in section to more clearly illustrate the various details of construction, and being taken on the line 1—1 of Fig. 2.

Fig. 2 is a transverse sectional view through my improved furnace and said view being taken on the line 2—2 of Fig. 1.

Fig. 3 is a sectional view longitudinally through the dome or double wall pipe and the upper end of the double wall drum and said view being taken on the line 3—3 of Fig. 1.

Fig. 4 is a transverse sectional view through a portion of the double wall pipe or drum depicted in Fig. 3, said view being taken on the line 4—4 of Fig. 3.

Fig. 5 is a sectional view through a portion of the lower half of the furnace illustrating the novel means I employ for adjustably supporting the drum defining the heating chamber, said view being taken on the line 5—5 of Fig. 2.

Fig. 6 is a sectional view through the adjustable support for the drum, said view being taken on the line 6—6 of Fig. 5.

Fig. 7 is a detail plan view of the supporting link or brace for the vertical standard used in adjustably supporting the drum.

Fig. 8 is a longitudinal sectional view through the intermediate front portion of the furnace depicting the novel means employed to separate the hot air chamber from the cold air chamber at the point where the drum and the outer casing are cut to permit the passage from the heater to the furnace doors, said view being taken on the line 8—8 of Fig. 2.

Fig. 9 is a transverse view taken through a portion of the outer casing and the inner

drum, said view being taken on the line 9—9 of Fig. 8, and

Fig. 10 is an enlarged detail sectional view of a portion of the top of the inner drum to more clearly illustrate the manner of separating the two concentric casings forming the drum.

As illustrated, the furnace is of well known type wherein the heater is surrounded by casings constituting two chambers one, the hot air chamber for conducting the hot air upwardly and, the other, a cold air chamber for conducting the cold atmosphere downwardly communicating with the hot air chamber at the base thereof.

The heater may be of any well known construction and design comprising an ash pit 1, fire box 2, combustion chamber 3 and hot air dome 4, separably united in a manner well known in the art and commonly practiced.

The heater is further provided with passages or chutes 5 communicating with the ash pit and combustion chamber whereby fresh fuel may be added to the heater at will and the burned out ashes readily removed. The air dome is also provided with a cleanout tubular projection 6 disposed above the chutes 5 to permit the ready access thereto for cleaning. Surrounding the heater 2 is a double wall drum 7 formed of two concentric casings 8 and 9 retained in spaced relation by means to be later described, and provided in their walls with a passageway or opening extending throughout the entire length thereof to permit the passage therethrough of the chute and tubular projection 5 and 6, the marginal ends of the casings 8 and 9 being directed toward each other into engagement as at 10 and secured in this position by means of the U-shaped clips 11 formed on the inner ends of partitions 12 which engage the adjacent portion of an outer casing 13 to be described.

The casing 13 surrounds the entire structure and is retained in spaced relation from the drum 7 to define therebetween a cold air chamber 14 to be later described, and has its wall adjacent the chute and tubular projections 5 and 6 cut away the greater portion of its length to accommodate said chute and projection. The outer ends of the chute and tubular projections 5 and 6 are closed by the usual doors, and the space surrounding the same where the casing 13 is apertured, is covered by means of a cast plate 15 which is secured to the extremities of the chute and tubular projection 5 and 6 and provides a rigid front wall portion contiguous with the outer casing. The face plate supports the doors for the passages and other fittings for the various parts leading to the furnace for cleaning or regulating purposes.

The furnace structure is supported upon a cast base 16, and the outer casing 13 has its lower end in snug engagement with an upstanding annular flange 17 formed on said base. The casings 8 and 9 are retained in their proper spaced relation by means of an upper and lower ring or hook 18 centrally provided with an annular laterally extending rib or re-enforcing flange 19 and to the inner face of each is spot welded or otherwise secured a plurality of U-shaped members 20 having a tongue member 21 struck from their inner walls and adapted to receive the adjacent portion of the casing 8 therebetween. The tongue member 21 has its lower end curved away from the wall of the U-shaped member 20 in order to insure the easy insertion of the casing 8 between the tongue 21 and the U-shaped member 20. The space between the casings 8 and 9 provides an intermediate air chamber between the cold air chamber 14 and the heating chamber 22 formed by the one casing 8 so that the air will not be heated prior to its entrance to the heating chamber 22 by the wall of the drum 7 and thus destroy the down draft of air through the chamber 14. The space between the casings 8 and 9 is left open at the top and bottom of the drum 7 so that a portion of the air in its passage from the chamber 14 will pass between the walls of casings 8 and 9 and thence outwardly at the top thereof and join and be commingled with the heated air from the chamber 22 as it passes therefrom into the double wall pipe section or dome 23 to be later described.

In order that the cold air chamber 14 will not be interrupted by the chute and tubular projection 5 and 6, the partitions 12 before described are employed. The partitions 12 have their outer free ends formed in the shape of a V or U to provide a resilient tongue 24 which insures a snug fit against the casing wall 13 and thus prevents the cold air from passing into the heating chamber 22 near its top. The partitions 12 are formed of any suitable sheet metal and permit the ready removal of the drum 7 from the furnace without dismantling the entire furnace.

It is particularly desirable that the lower end of the drum 7 be on a plane parallel with the top of the ash pit of the heater, and I provide a vertically adjustable support, capable of use with heaters of various sizes and includes a series of vertical supporting standards 25 having provided near their upper ends with a plurality of saw teeth 26, the standards 25 being T-shaped in cross section, and said teeth being formed on the leg of the T. Slidably mounted upon each standard 25 is a plate 27 having an opening therein corresponding with the shape of the standard 25 and having the

edge 28 surrounding the portion of the opening shaped to form a suitable locking means for engaging any one of the teeth 26. When the plate 27 is locked to the standard in adjusted position, its portion engaging the standard will be downwardly and inwardly inclined, a hooked lug 29 extending inwardly therefrom substantially horizontal, said hooked lug 29 receiving the lower end 10 of the ring 18 secured to the casing 9, whereby the drum is supported within the casing 13. When it is desired to change the adjustment of the drum 7, the plate 27 is moved so that its portion surrounding the 15 standard 25 is substantially horizontal when the same will be free to move up and down the standard 25.

The standards 25 have their lower ends tapered as at 30 to be detachably engaged 20 in the sockets 31 formed in link members 32 having their ends secured to the ash pit section 1 by means of fastenings 33 and to the base 16 by means of fastenings 34. The link members 32 also serve to provide means 25 for retaining the base member 16, and consequently the casing 13, in the proper spaced relation with reference to the heater.

The entire furnace structure is adapted to be disposed directly under the ground floor 30 of a house in which is mounted a suitable register plate or grating 35, and the outer casing 13 has its walls inclined upwardly and inwardly just above the heating chamber 22 and is connected with the grating 35 plate 35 by a section 36. In order to adapt 35 the furnace for floors of various heights, the section 36 above the inclined wall portion of the casing 13 may be varied in length in order that the proper adjustment may be 40 had. A cylindrical pipe section 37 also extends upwardly from the top end of the dome 23 to engage an annular flange 38 formed on the under side of grating 35 to thus provide a passageway for conducting 45 the heated air from the chamber 22 out through the register.

The dome 23 is of novel construction and is formed of two complementary sections 39 each formed from a single sheet of material 50 which has been formed in a plain cylinder and then placed in a stamping machine and plaited or ribbed as at 40 whereby the walls are inclined upwardly and inwardly. The ribs 40, besides giving the shape to the sections 39, form substantially re-enforcing means for the dome as will be at once apparent. The upper smaller ends of the sections are beaded as at 41 and the portions above the beads 41 directed upwardly in a 55 straight line as at 42. The lower ends of the sections 39 are struck laterally and then downwardly as at 43 to provide flanges for engaging the uppermost annular ring 18.

The dome 23, as before stated, consists of 60 two of the sections 39 nested together as

best shown in Figures 1 and 3 whereby a stronger structure is had, having the walls thereof separated by a dead air space 44. The dead air space 44 is provided by the bead 41 of the innermost section 39 abutting 70 the adjacent wall portion of the outermost section 39, preventing the walls of the same from engaging and the downwardly extending flanges 43 of the sections are engaged as best shown in Fig. 3.

The top edge of the portion 42 of the outermost section 39 is preferably turned 75 inwardly a slight distance for convenience in fitting the pipe section 37.

In operation, the cold air passes through 80 the apertures in the register plate 35 outwardly of its central flange 38 and down through the chamber 14, thence under the bottom of the drum 7 into the heating chamber where it is heated and rises upwardly 85 through the dome 23, pipe section 37, and out the openings in the register plate 35 within the flange 38. The portion of the air which passes downwardly through the chamber 14 passes between the casings 8 and 90 9 forming the drum 7, thus insulating the drum 7 from the chamber 14, and prevents the air in said chamber from becoming heated prior to its entrance to the heating chamber to thus insure the proper circulation 95 through the furnace, the air passing between the casings 8 and 9 passing therefrom at the top of the drum and co-mingling with the heated air from chamber 22. The dead air space 44 of the drum 23 also serves 100 to insulate the space within the drum 23 and prevents the retardation of the air circulation in the furnace by the cold air in the chamber 14 becoming heated prior to its entrance to the heating chamber 22.

Heretofore, it has been common practice 105 to form the domes 23 from a blank of material cut so that when its ends are brought together and riveted or otherwise secured, a dome is formed provided with upwardly and inwardly inclined walls. This method is extremely wasteful in material in that, to cut the blank in the desired shape, the longitudinal edges of the blank must be curved, and consequently when cut from a sheet of material of a given size, the number obtained from one sheet is greatly reduced, and the material cut away, of absolutely no use whatsoever. Consequently, one of the main advantages obtained by my 110 method of forming the dome 23 is that the waste of material is practically nil, and a greater number of blanks cut from a single sheet of material. As hereinbefore described, I form the domes 23 from a single 115 blank of material of rectangular form, which may be of one piece or of several pieces secured together, having its ends secured together to form a plain cylindrical casing. The casing thus formed is then 120 125 130

plaited or ribbed to provide the inclined walls.

Another important advantage obtained by forming the dome by my method is that the walls thereof are greatly re-enforced by means of the ribs or plaiting which serve to produce the proper inclination to the walls.

What I claim as my invention is:

1. A heating furnace, comprising an outer 10 casing, an inner casing of less diameter than said outer casing and positioned therein with its walls spaced from the walls of said outer casing to form an air passage, a heater within the inner casing and spaced from the 15 walls thereof to form a heating chamber, and means for vertically adjustably supporting said inner casing and holding the same in spaced relation between the fire pot and the outer casing.
- 20 2. A heating furnace, comprising an outer casing, an inner casing of less diameter than said outer casing and positioned therein with its walls spaced from the walls of said outer casing to form an air passage, a heater 25 within the inner casing and spaced from the walls thereof to form a heating chamber, and means engaging the lower edge of the inner casing for substantially readily vertically adjustably supporting the same in said 30 outer casing.
3. A heating furnace, comprising an outer casing, an inner casing of less diameter than said outer casing and positioned therein with its walls spaced from the walls of said outer 35 casing to form an air passage, a heater within the inner casing and spaced from the walls thereof to form a heating chamber, and means for vertically adjustably supporting said inner casing and holding the same 40 in spaced relation between the fire pot and the outer casing, said means consisting of a vertical standard adjacent the lower portion of the inner casing and having teeth formed therein and a member having one end slidably mounted on the standard and engageable with any one of the teeth and its other end engaged with said inner casing to support the same.
4. A heating furnace, comprising a heater 50 having a tubular projection extended therefrom, an inner casing surrounding said heater and having a cut away portion to permit the passage therethrough of said heater projection, said casing being spaced from the 55 heater to provide a heating chamber, an outer casing surrounding said inner casing with its walls spaced therefrom to provide an air inlet and having a cut away portion to permit the passage therethrough of said

heater projection, and partition members 60 carried by one of said casings adjacent its cut away portion and having their free ends normally resiliently bearing against but not attached to the adjacent wall portions of the other casing to close the air inlet where the 65 heater projection passes therethrough.

5. A heating furnace of the class described comprising a heater having passages projecting therefrom, an outer casing surrounding said heater and provided with an opening in 70 its wall for the heater passages, an inner casing spaced from said outer casing and vertically adjustably positioned therein and provided with an opening in its wall for the 75 heater passages, and partitions having their inner ends secured to the marginal edges of the opening in the inner casing and their outer ends resiliently engaging but not attached to the wall of the outer casing adjacent the marginal edges of the opening 80 therein to form an area-way for said heater passages.

6. A heating furnace of the class described comprising a heater having passages projecting therefrom, an outer casing surrounding said heater and provided with an opening in its wall for the heater passages, an inner casing spaced from said outer casing and provided with an opening in its wall for the 85 heater passages, and partitions having their inner ends secured to the marginal edges of the opening in the inner casing and their outer ends provided with a spring bend which resiliently engages but is not attached to the walls of the outer casing adjacent the 90 marginal edges of the opening therein to form an area-way for said heater passages.

7. A heating furnace of the class described comprising a heater having passages projecting therefrom, an outer casing surrounding said heater and provided with an opening in its wall for the heater passages, a drum within the casing and surrounding the heater and including two concentric casings of different diameters to provide an air space 100 therebetween, said casings forming the drum having openings in their walls for the heater 105 passages, clip members engaging the adjacent marginal edges of the openings in said drum casings to secure said casings together at said edges, and means carried by said clip members and extending resiliently outwardly to abut but not attached thereto the wall of the outer casing near the marginal edges of its opening to provide an area-way for said heater passages.

In testimony whereof, I affix my signature.
CHARLES M. BULLER.
